US0D1051587S

(12) **United States Design Patent** (10) **Patent No.:** **US D1,051,587 S**
(45) **Date of Patent:** **** Nov. 19, 2024**

(54) **NIGHTLY DOSE PACKET STORAGE SYSTEM**

(71) Applicant: **Flamel Ireland Limited**, Dublin (IE)

(72) Inventors: **William J. Schaefer**, St. Louis, MO (US); **Jenny Reid**, St. Louis, MO (US); **Heather Kruchowski**, St. Louis, MO (US)

(73) Assignee: **Flamel Ireland Limited**, Dublin (IE)

(**) Term: **15 Years**

(21) Appl. No.: **29/827,076**

(22) Filed: **Feb. 17, 2022**

(51) LOC (14) Cl. **03-01**

(52) U.S. Cl.

USPC **D3/203.1**

(58) **Field of Classification Search**

(57) **CLAIM**

The ornamental design for a nightly dose packet storage system as shown and described.

DESCRIPTION

FIG. 1 is an exploded, isometric view of a nightly dose packet storage system comprising four Large Containers, each with seven nightly dose packets, and a Receptacle with a Mixing Cup and a Small Container with two nightly dose packets;

FIG. 2 is a top, isometric view of the nightly dose packet storage system shown in an assembled configuration; and FIG. 3 is a top plan view thereof.

FIG. 4 is a top, isometric view of one of the four Large Containers shown removed from the nightly dose packet storage system for clarity of disclosure;

FIG. 5 is a front elevational view thereof;

FIG. 6 is a rear elevational view thereof;

FIG. 7 is a right side elevational view thereof;

FIG. 8 is a left side elevational view thereof;

FIG. 9 is a top plan view thereof;

FIG. 10 is a bottom plan view thereof;

FIG. 11 is a cross-sectional view taken in the direction of line 11-11 of FIG. 9; and

FIG. 12 is a top, isometric view of the Large Container in FIG. 4 in an environment of use.

FIG. 13 is a top, isometric view of the Small Container shown removed from the nightly dose packet storage system for clarity of disclosure;

FIG. 14 is a front elevational view thereof;

FIG. 15 is a rear elevational view thereof;

FIG. 16 is a right side elevational view thereof;

FIG. 17 is a left side elevational view thereof;

FIG. 18 is a top plan view thereof;

FIG. 19 is a bottom plan view thereof; and

FIG. 20 is a top, isometric view of the Small Container in FIG. 13 in an environment of use.

FIG. 21 is a top, isometric view of the Receptacle shown removed from the nightly dose packet storage system for clarity of disclosure;

FIG. 22 is a front elevational view thereof;

FIG. 23 is a rear elevational view thereof;

FIG. 24 is a right side elevational view thereof;

FIG. 25 is a left side elevational view thereof;

FIG. 26 is a top plan view thereof; and

FIG. 27 is a bottom plan view thereof.

FIG. 28 is a top, isometric view of the Receptacle in FIG. 21 in an environment of use with the Mixing Cup and the Small Container;

FIG. 29 is a front elevational view thereof;

FIG. 30 is a rear elevational view thereof;

FIG. 31 is a right side elevational view thereof;

FIG. 32 is a left side elevational view thereof;

FIG. 33 is a top plan view thereof; and,

FIG. 34 is a bottom plan view thereof.

The broken lines depict portions of the nightly dose packet storage system that form no part of the claimed design.
